(57) **CLAIM**

The ornamental design for a syringe, as shown and described.

DESCRIPTION

FIG. 1 is a perspective view of an embodiment of a syringe according to our new design;

FIG. 2 is a top plan view of the syringe shown in FIG. 1; FIG. 3 is a bottom plan view of the syringe shown in FIG. 1;

FIG. 4 is a front elevational view of the syringe shown in FIG. 1;

FIG. 5 is a rear elevational view of the syringe shown in FIG. 1;

FIG. 6 is a right side elevational view of the syringe shown in FIG. 1; and,

FIG. 7 is left side elevational view of the syringe shown in FIG. 1.

The broken line showing is for illustrative purposes only and forms no part of the claimed design.
